UNITED STATES PATENT OFFICE

2,676,176

MANUFACTURE OF PYRIMIDINE DERIVATIVES

Charles Henry Vasey, Blackley, Manchester, England, assignor to Imperial Chemical Industries Limited, a corporation of Great Britain

No Drawing. Application March 31, 1952,
Serial No. 279,687

Claims priority, application Great Britain
April 6, 1951

4 Claims. (Cl. 260—260)

1

This invention relates to improvements in the manufacture of pyrimidine derivatives which possess useful anti-convulsant properties. The pyrimidine derivatives with which this invention is concerned are those of the formula

wherein R_1 stands for a monocyclic carbocyclic radical or for an alkenyl radical of not more than 3 carbon atoms, R_2 stands for an alkyl radical or for an alkenyl radical of not more than 3 carbon atoms and R_3 stands for hydrogen or for an alkyl radical of not more than 4 carbon atoms which are the subject of U. S. Patent 2,576,279 of November 27, 1951.

According to the invention we manufacture the said pyrimidine derivatives by a process which comprises reducing compounds of the formula

wherein R_1 , R_2 and R_3 have the meaning stated above and wherein R_4 stands for an alkyl radical, an alkenyl radical or an aralkyl radical.

According to a further feature of the invention the said pyrimidine derivatives are manufactured by a process which comprises reducing compounds of the formula:

or their hydrates or salts wherein R_1 , R_2 and R_3 have the meaning stated above.

The starting materials are the subject of copending British application No. 8020/51 which corresponds to U. S. application Serial No. 279,686, now U. S. Patent 2,666,056 of January 12, 1954, of even date herewith and may be obtained by processes described in that specification.

The processes of reduction of the present invention may be brought about by the conventional methods, for example by means of zinc and acetic acid; by means of boiling formic acid or formamide either alone or in a solvent for example dimethylformamide; by heating with a hydrogen-containing catalyst, for example W5 Raney nickel; by means of hydrogen in presence of a catalyst, for example Raney nickel or palladised strontium carbonate.

It is to be understood that when the compound to be reduced contains an unsaturated

radical, for example a cyclohexenyl or alkenyl radical, which it is desired to retain in the final compound, the reduction process should be a mild one, as by means of boiling formic acid or of formamide.

The invention is illustrated but not limited by the following examples in which the parts are by weight.

Example 1

10 2 parts of 2-ethoxy-5-phenyl-5-ethylhexahydropyrimidine-4:6-dione, in 250 parts of ethanol are stirred with 1 part of Raney nickel catalyst and hydrogen at 50 atmospheres pressure at 90° C. for 5 hours. The mixture is then cooled to 75° C. and filtered. The filtrate is evaporated to small volume and cooled. 5-phenyl-5-ethylhexahydropyrimidine-4:6-dione, M. P. 281° C., is filtered off and dried.

The same product is obtained when the starting material is 2-n-propoxy-, 2-isopropoxy-2-n-butoxy-, 2-sec.-butoxy-, 2-allyloxy- and 2-benzyl-oxy-5-phenyl-5-ethylhexahydropyrimidine - 4:6-diones.

Example 2

20 2 parts of 2-ethoxy-5-phenyl-5-ethylhexahydropyrimidine-4:6-dione are boiled under reflux with 50 parts of formamide for half an hour. The mixture is then cooled and filtered and 5-phenyl - 5 - ethylhexahydropyrimidine-4:6-dione, M. P. 281° C., is obtained by crystallisation of the solid residue from ethanol.

Example 3

25 3 parts of 2-ethoxy-5-phenyl-5-ethylhexahydropyrimidine-4:6-dione are heated under reflux with 100 parts of 98% aqueous formic acid for 4 hours. Approximately 90 parts of formic acid are then distilled off and the residue is cooled and filtered. 5-phenyl-5-ethylhexahydropyrimidine-4:6-dione is obtained, M. P. 281° C.

Example 4

30 3 parts of 2-ethoxy-5-phenyl-5-ethylhexahydropyrimidine-4:6-dione are boiled under reflux with 100 parts of dimethylformamide and 10 parts of 98% aqueous formic acid. A further 30 parts of formic acid are then added in lots of 10 parts once an hour. The mixture is then boiled under reflux for one hour longer and then distilled to small volume and cooled and filtered. The residual solid is 5-phenyl-5-ethylhexahydropyrimidine-4:6-dione, M. P. 281° C.

Example 5

35 2 parts of 5-phenyl-5-ethyltetrahydropyrimi-

dine-4:6-dione and 250 parts of ethanol are boiled under reflux for 2 hours with 20 parts of hydrogen-containing Raney nickel (prepared by method W5 as described in J. A. C. S., 1948, 70, 695). The mixture is then filtered and evaporated to small volume and cooled and again filtered. The solid residue consists of 5-phenyl-5-ethylhexahydropyrimidine-4:6-dione, M. P. 281° C.

Example 6

5 parts of zinc dust are added to a solution of 1 part of 2-ethoxy-5-phenyl-5-ethylhexahydropyrimidine-4:6-dione in 30 parts of 50% aqueous acetic acid. 2 parts of concentrated hydrochloric acid are then added and the mixture is heated at 95-100° C. for 30 minutes, then allowed to cool to room temperature during 15 hours. It is then filtered and the solid residue is washed with water and extracted with 50 parts of boiling 80% ethanol. The filtrate is cooled and filtered. The solid residue consists of 5-phenyl-5-ethylhexahydropyrimidine-4:6-dione, M. P. 281° C.

Example 7

10 parts of 5-phenyl-5-ethyltetrahydropyrimidine-4:6-dione, 2 parts of palladised strontium carbonate and 1000 parts of ethanol are stirred together at 90-100° C. in an atmosphere of hydrogen at a pressure of 108 atmospheres for 5 hours. The mixture is then filtered and the filtrate is evaporated to small volume and cooled. 5-phenyl-5-ethylhexahydropyrimidine-4:6-dione, M. P. 281° C., is obtained by filtration.

Example 8

10 parts of 2-methoxy-5-phenyl-1-methyl-5-ethylhexahydropyrimidine-4:6-dione, 2 parts of Raney nickel catalyst and 750 parts of ethanol are stirred together for 5 hours at 100° C. in an atmosphere of hydrogen at a pressure of 100 atmospheres. The mixture is then filtered hot and the filtrate is evaporated to small volume and cooled and filtered. The solid residue consists of 5-phenyl-1-methyl-5-ethylhexahydropyrimidine-4:6-dione, M. P. 185-186° C.

Example 9

1 part of 2-ethoxy-5- $\Delta^{2,3}$ -cyclohexenyl-5-ethylhexahydropyrimidine-4:6-dione is boiled under reflux with 5 parts of formamide for 90 minutes. The mixture is then cooled and filtered and the solid residue is crystallised from methanol to give 5- $\Delta^{2,3}$ -cyclohexenyl-5-ethylhexahydropyrimidine-4:6-dione, as a colourless solid, M. P. 268° C.

Example 10

1 part of 2-ethoxy-5-phenyl-5-methylhexahydropyrimidine-4:6-dione is boiled under reflux

for 2 hours with 100 parts of ethanol and 10 parts of hydrogen-containing (W5) Raney nickel (cf. J. A. C. S., 70, 695 (1948)). The mixture is then filtered and the filtrate is evaporated to small volume and cooled and filtered. The solid residue consists of 5-phenyl-5-methylhexahydropyrimidine-4:6-dione, M. P. 296° C.

Example 11

A solution of 10 parts of 5-phenyl-5-ethyltetrahydropyrimidine-4:6-dione monohydrochloride in 200 parts of glacial acetic acid is shaken in an atmosphere of hydrogen with 1 part of Adam's platinum oxide catalyst at room temperature until no further hydrogen is absorbed. The product is then heated to 95-100° C. and filtered. The filtrate is distilled under reduced pressure and the residue is crystallised from ethanol. 5-phenyl-5-ethylhexahydropyrimidine-4:6-dione, M. P. 281° C., is obtained.

The same product is obtained starting from 5-phenyl-5-ethyltetrahydropyrimidine-4:6-dione monohydrate.

What I claim is:

25 1. A process for the manufacture of pyrimidine derivatives of the formula

30 wherein R_1 stands for a phenyl radical and R_2 stands for an alkyl radical of not more than 3 carbon atoms which comprises reducing a compound of the formula

40 wherein R_1 and R_2 have the meaning stated above and wherein R_3 stands for a radical selected from the group consisting of alkyl and aralkyl radical.

2. Process as claimed in claim 1 wherein the reduction is brought about by means of hydrogen in presence of a hydrogenation catalyst.

45 3. Process as claimed in claim 2 wherein the hydrogenation catalyst is a finely divided metal selected from the group consisting of nickel, cobalt, platinum and palladium.

50 4. Process as claimed in claim 1 wherein the reduction is brought about in the presence of boiling formamide.
